[57] CLAIM

The ornamental design for a novelty figurine, as shown and described.

DESCRIPTION

FIG. 1 is a perspective view of a novelty figurine embodying my new design;

FIG. 2 is a front view thereof;

FIG. 3 is a side plan view thereof;

FIG. 4 is a back view thereof;

FIG. 5 is an opposite side plan view thereof;

FIG. 6 is a bottom plan view thereof; and,

FIG. 7 is a top plan view thereof.

The broken line showing of hat and diploma are for illustrative purposes only and form no part of the claimed design.
